Inventor.
JAMES J. HENNESSY.

By Rodney Bedell. *Attest:*

UNITED STATES PATENT OFFICE.

JAMES J. HENNESSY, OF NEW YORK, N. Y.

LUBRICATOR.

Application filed May 22, 1923. Serial No. 640,646.

My invention relates to journal box lubricators such as are used upon railroad rolling stock and consists in a modification of my copending application Serial Number 578,-
5 018, filed July 27, 1922.

The particular object of my present invention is to afford a gravity-operated return device for the pump plunger to be used in place of the return spring shown in the 10 above-mentioned application, and, in the accompanying drawings illustrating my present invention,—

Figure 1 is a vertical longitudinal section through my improved lubricator.

15 Figure 2 is a vertical transverse section on line 2—2 of Figure 1.

In these drawings, A represents the axle of a wheel to be lubricated and B indicates the collar or flange of the wheel which operates the lubricator. The body of the lubricator is box-like in general appearance and comprises a bottom wall 1 and side wall 2 from the former of which rises a central projection or wall 3 and adjacent thereto a 25 cylindrical projection 4. The lower portion of wall 3 is provided with a horizontal passage 5 which forms a pump cylinder and receives the sliding plunger 6 equipped with a flop valve 7. The inner end of passage 5 communicates with the lower end of cylinder 4 and upon operation of the plunger supplies lubricant to the axle through cylinder 4 which is equipped with a ball check 8.

The plunger 6 is moved back and forth by 35 a rod 9 provided with a rigid connection 10 to plunger 6. Rod 9 extends through the side wall 2 of the lubricator body and is adapted to contact at its outer end with the collar or flange B of the wheel. The inner 40 end of rod 9 is slidably journaled in wall 3 and projects into a recess 11 formed in the upper part of the latter. Extending through recess 11 at right angles to rod 9 and plunger 6 is a pintle 12 journaled in 45 the wall 3 at opposite sides of recess 11. This pintle has a finger 13 fixed to its middle portion and extending upwardly into contact with the inner end of rod 9. Secured to the outer ends of pintle 12 are weights 50 14. It will be noted that these are secured

off-center or eccentrically so that they are held by the pintle, finger 13 and rod 9 in such position that their weight tends to turn the pintle and finger 13 to move rod 9 to the left. The weights, pintle, and finger form 55 a yielding device for returning rod 9 and plunger 6 to the left after each movement of these parts to the right by the thrust of the wheel element B.

As is well known, there is always play of 60 the wheel and axle to and fro in the journal box and this play is utilized by the type of lubricator illustrated to pump the lubricant from the reservoir formed by the lubricator box to the axle or to waste held in contact 65 with the axle by any suitable means, such as the pan 15 illustrated which is yieldingly supported against the axle by spring 16.

The construction shown in my present invention may be advantageously employed 70 at times when the spring shown in the above-mentioned application is undesirable. It is not subject to variations as are ordinary manufactured springs, nor will it crystallize and break as springs of poor quality 75 often do.

The rod and plunger connection 10 may be adjusted lengthwise of rod 9 without interference by the return device as is the case with the spring construction shown in my 80 copending application.

I claim:

1. In a journal lubricator, a horizontal pump cylinder, a piston in said cylinder, a wall above said cylinder, a transverse pintle 85 journaled in the upper portion of said wall, weights at the sides of said wall fixed off-center on the ends of said pintle, an up-standing finger fixed to the middle of said pintle, a horizontal slideable rod engaging 90 said finger and extending outside of said lubricator to contact with a movable actuating element, and a rigid connection between said rod and said piston.

2. In a journal lubricator, a box-like lub- 95 bricant reservoir, a wall in said reservoir having a passage in its lower portion forming a pump cylinder, a plunger therein, a recess in the upper portion of said wall, a pintle extending at right angles to said cyl 100

inder passage through said recess and journaled in the walls thereof, weights eccentrically fixed on said pintle at the sides of said walls, a finger fixed on the middle of said pintle in said recess, an actuating rod parallel with said plunger extending through an outer wall of said reservoir to contact

with a wheel hub or the like and extending through a wall of said recess to contact with said finger, and a rigid connection between said rod and said plunger.

In testimony whereof I hereunto affix my signature this 12th day of May, 1923.

JAMES J. HENNESSY.
